[57] **CLAIM**

The ornamental design for a combined holder for writing instruments and note paper, substantially as shown and described.

DESCRIPTION

FIG. 1 is a right front perspective view of a combined holder for writing instruments and note paper showing my new design;

FIG. 2 is a front elevational view thereof;

FIG. 3 is a top plan view thereof;

FIG. 4 is a bottom plan view thereof;

FIG. 5 is a rear elevational view thereof; and

FIG. 6 is a right side elevational view thereof, the left side being a mirror image thereto.

FIG.1

FIG.2

FIG.3
